UNITED STATES PATENT OFFICE

HUGO JUNKERS, OF DESSAU, GERMANY

RIVETING DEVICE

Original application filed July 27, 1926, Serial No. 125,204, and in Germany August 21, 1925. Divided and this application filed January 3, 1930. Serial No. 418,249.

My invention refers to the riveting of tubes or other hollow work pieces as described in my copending application for patent of the United States, Serial No. 125,204, filed July 27, 1926, according to which an anvil is inserted in the tube and held in position therein by resilient means in such manner as to give way under the pressure of the shaft of a rivet which is introduced through a hole in the wall of the tube or the like.

The rivet forces back the resiliently supported anvil, and if blows are now struck on the swage head of the rivet, the inertia of the anvil will upset the rivet shaft to form the closing head. After the anvil has thus acted on the shaft of the rivet, it is jerked back by the resilient means supporting it and then returns into its initial position in which it is ready for reacting under the next blow struck on the swage head.

It is an object of my invention to improve a device of this kind.

In the drawing affixed to this specification and forming part thereof a device embodying my invention is illustrated diagrammatically by way of example, as applied to the tubular work piece to be riveted.

In the drawing.

Fig. 1 is an axial section of the anvil and the tube on the line I—I in Fig. 2, and

Fig. 2 is a section on the line II—II in Fig. 1.

Referring to the drawing, 1 is a tube to be riveted, 4 is a solid substantially cylindrical anvil having a smaller diameter than the inside diameter of the tube, the ends of the anvil being slightly tapered or otherwise reduced in order to facilitate its introduction. 90 and 91 are cables or the like by which the anvil is fed through the tube, 84, 85, and 86, 87 are bores extending across the anvil, and 75, 76, are spacing members projecting from the anvil at opposite ends of the bores. 79, 80 and 81, 82 are springs supported on a partition 88 in each bore and tending to force the spacing members outwardly.

These members may be designed in various ways. For instance the members in the bore 84 have the form of plug-like bodies 75 which are fitted to slide in the reduced end por-

tions 77 of the bore 84 and are provided with shoulders 89 which prevent them from being forced out of the bores by the springs 79, 80.

In the bore 85 and also in the bores 86 and 87, balls 76, 76 are inserted at either end. The end portions of the bores are reduced to a diameter which is less than the diameter of the balls so that the balls cannot be forced out of the bores by the springs 81, 82.

The parts 75, 76 are preferably distributed over the perimeter of the anvil in such manner that in its initial position the anvil is substantially coaxial with the tube 1, but is spaced from the walls of the tube, as its diameter is less than the inside diameter of the tube 1.

When a rivet 8 (Fig. 2) is inserted in a hole of the tube wall and its swage head is struck by the riveting tool 9, the resilient reaction of the anvil will form a closing head on the rivet in the manner above described, the blows on the tool 9 being followed by reaction blows of the anvil 4 upon the inner end of the rivet 8 which is then upset due to the resilient mounting of the anvil.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:

1. In apparatus for riveting tubes in combination, an anvil adapted to serve as an abutment for the rivet and members resiliently mounted in, and partly projecting from cavities of said anvil for spacing same on all sides against the inner wall of the tube to be riveted, said anvil consisting of a relatively substantial mass which by virtue of the resilient holding means is capable of delivering blows upon the inner end of the rivet, incident to its reaction following blows applied to the outer end of the rivet.

2. In apparatus for riveting tubes in combination, an anvil adapted to serve as an abutment for the rivet, springs mounted in radial borings of said anvil and spacing members partly projecting from said borings under the action of said springs, said anvil consisting of a relatively substantial mass which by virtue of the resilient holding means is capable of delivering blows upon the inner 10 end of the rivet, incident to its reaction following blows applied to the outer end of the rivet.

In testimony whereof I affix my signature.
HUGO JUNKERS.
